Primary Examiner — Catherine Ho(74) *Attorney, Agent, or Firm* — CANTOR COLBURN LLP(57) **CLAIM**

The ornamental design for a label, as shown and described.

DESCRIPTION

FIG. 1 is a top view of the first embodiment of a label, showing my new design;

FIG. 2 is a bottom view thereof;

FIG. 3 is a side view thereof;

FIG. 4 is another side view thereof;

FIG. 5 is a front view thereof;

FIG. 6 is a back view thereof;

FIG. 7 is a perspective view thereof;

FIG. 8 is a top view of the second embodiment of a label;

FIG. 9 is a bottom view thereof;

FIG. 10 is a side view thereof;

FIG. 11 is another side view thereof;

FIG. 12 is a front view thereof;

FIG. 13 is a back view thereof; and,

FIG. 14 is a perspective view thereof.

The broken line portion of the figure drawings is included to show portions of the article that form no part of the claimed design. The dash-dot lines define the bounds of the claimed design and form no part thereof.

1 Claim, 2 Drawing Sheets---
